UNITED STATES PATENT OFFICE

108,823

DESIGN FOR A VEHICLE BODY

Jack Barofsky, New York, N. Y.

Application November 5, 1937, Serial No. 72,632

Term of patent 14 years

To all whom it may concern:

Be it known that I, Jack Barofsky, a citizen of the United States, residing at 1451 Broadway, Room 603, in New York County and State of New York, have invented a new, original, and ornamental Design for a Vehicle Body, of which the following is a specification, reference being had to the accompanying drawing, forming part thereof.

The figure is a side perspective view of a vehicle body, showing my new design.

The side opposite that shown in the drawing is the same as illustrated. The rear end is plain.

The dominant features of my design are shown in solid lines in the drawing.

I claim:

The ornamental design for a vehicle body, as shown and described.

JACK BAROFSKY.
